UNITED STATES PATENT OFFICE.

PAUL HAUSSMANN, OF BURG, NEAR MAGDEBURG, GERMANY.

PULSOMETER.

SPECIFICATION forming part of Letters Patent No. 703,788, dated July 1, 1902.

Application filed January 13, 1902. Serial No. 89,491. (No model.)

To all whom it may concern:

Be it known that I, PAUL HAUSSMANN, engineer, a subject of the German Emperor, residing at Burg, near Magdeburg, in the Empire 5 of Germany, have invented certain new and useful Improvements in and Relating to Pulsometers, of which the following is a specification.

This invention relates to steam water-lifters 10 or pulsometers, and more particularly to the construction of the injecting nozzles or devices which produce the condensation of the steam in the interior of the pulsometer-chambers. The said injecting nozzles or devices 15 are so arranged as to render the injector-tube adjustable, while the mouth of such tube is adapted to act in conjunction with a spraying device provided in the interior of the said chambers. With this arrangement it is possible 20 to regulate the quantity of the refrigerating-water to the existing conditions of working, (suction-head, head of pressure, steam-pressure, &c.) This is important for the economical use of the pulsometer, inasmuch 25 as the introduction of too small quantities, as also unduly large quantities, of refrigerating-water unfavorably affects the economical efficiency as well as the general working capacity of the pulsometer. The regulation 30 can be effected during working from the exterior. It is essential that the water-sprayer coacting with the adjustable mouth of the injecting-tube in the interior of the chamber and the parts for carrying it should be outside 35 the injector-pipe. The refrigerating-water flows through the injector-pipe in a full jet until it reaches the mouth, where the division of the water-jet is effected. By this means 40 it is impossible for the injector-pipe to become choked by foreign substances, and thus cause an imperfect function of the apparatus.

The device adapted to coact with the injector-pipe for spraying the water may advantageously be constructed in such a manner as 45 to cause the full water-jet to spread in the form of a trumpet, and thereby effect an expeditious and energetic condensation of the steam. The supply of the injector-water is effected by connecting each injector-pipe by 50 means of a flexible or yielding pipe with the

opposite chamber or with another pressure-chamber.

The invention is shown in the annexed drawings in two forms of construction.

Figure 1 shows a front elevation, partly in 55 section, of one form of pulsometer constructed in accordance with this invention. Fig. 2 is a section taken on the line A B of Fig. 1. Fig. 3 is a section taken on the line C D of Fig. 2. Fig. 4 is a separate view, drawn to a 60 larger scale, of the injecting device. Fig. 5 is a modified construction of the injector device.

The pulsometer is mainly of ordinary form. The two chambers $k k'$, Fig. 2, are connected, 65 by means of channels j , with the valve casing or chamber z , which latter comprises the suction-chambers $m m'$, provided with suction-valves $x x'$, respectively, which correspond to the said chambers $k k'$. The valve casing 70 or chamber z further comprises the pressure or forcing chamber n , with the pressure-valves $y y'$. The steam is supplied through the pipe t , fitted with valve u . The two injector devices are shown at s and s' in Figs. 75 1 and 2.

One of the two injector devices connected with the pulsometer shown in Figs. 1 and 2 is shown on a larger scale in Fig. 4.

In the injecting device, Fig. 4, the injector-pipe a is adapted to be slid endwise for its entire length. For this purpose the said injector-pipe a is carried by a membrane i , which forms a tight joint for the tube a with regard to the injector-chamber. The membrane is firmly clamped between the flange g' and ring g^2 , which latter are together fixed in position upon the pulsometer, as indicated in Fig. 1, so that the said injector-pipe a extends through the opening s^3 into the interior 85 of the chamber.

The means for adjusting the position of the injector-pipe a are as follows: The lower part of the injector-pipe a rests upon a steel screw f , which is screwed into an arm or bow-piece 95 g . Thus by screwing the set-screw f the injector-pipe a can be displaced in its longitudinal direction.

The division of the injector-water is effected by the aid of a cone c , covering the mouth 100

b of the injector-pipe a. This cone c is fixed to a carrying strap or bow l, which may be suitably fixed to the part g'. It is important also that the parts which carry the cone c are 5 outside of the injector-pipe a.

The injector-pipe a is conveniently provided with a lateral socket or tube connection, to which is attached the conduit for the pressure-water. The flow of the pressure-jet is 10 indicated by the arrow in Fig. 4. In the arrangement shown in Figs. 1 and 2 the injector-pipe a of the chamber k' is connected with the other chamber k by a flexible tube d'. In the same manner the injector device 15 of the chamber k may be connected, by means of a flexible conduit d', with the chamber k'. In Figs. 1 and 2, however, the second injector-pipe a of the chamber k is connected by a flexible pipe d with the pressure-chamber 20 n by connecting the pipe d to the tube connection o' of the pressure-conduit o. The injector-pipe is guided movably in the socket g', arranged on the flange g'. The tight joint is formed, as previously stated, by the clamp- 25 ing-membrane i, which latter forms in a certain manner the bottom of the chamber k or k' and closes the space g' from the exterior. The membrane is preferably made of metal, so that it is able to offer resistance enough 30 against the greatest pressure in the chamber.

The action of the pulsometer is known. The two chambers k k' are alternately affected 35 by the reversing-valve u, so as to be emptied by the steam-pressure and filled through the condensation of the steam, followed by the sucking action, whereby the suction-valves x and x' and pressure-valves y y' effect the delivery of the water in the known manner.

As soon as one of the chambers has been 40 emptied and filled with steam and after the valve u has reversed the action the injector device introduces the refrigerating-water into such steam-filled chamber by the action of the pressure in the other chamber or the 45 pressure existing in the chamber n or pressure-conduit o, so that an effective condensation and an energetic suction is produced through the injection. By the adjustment of the injector-pipe a upwardly or downwardly 50 the quantity of injection-water may be increased or decreased.

In the modified arrangement of injector de-

vice shown in Fig. 5 the pipe a is movably guided in the plate v² through a stuffing-box v v'. The part v² is secured in front of the 55 opening s² in a similar manner, as previously described with reference to the plate or flange g', Fig. 1. The plate v² is furnished with the strap or bow for the spraying-cone c and with an arm g for the set-screw f. 60

The details may be varied. The arrangement of the pulsometer may be so carried out that either both flexible pipes d' of the two injector devices are connected with the pressure-pipe o or with the chamber n or that 65 both flexible pipes are connected like the pipe d' with the corresponding chamber k or k', respectively. In the latter case the two pipes would cross one another. The injector device may be used in connection with various 70 kinds of pumps or pulsometers. The adjusting means for the injector-pipe may be of any convenient form or type. For example, the adjustment of the injector-pipe may be effected by revolving it or otherwise conveniently. The spraying means may be of any 75 other form.

What I claim, and desire to secure by Letters Patent of the United States, is—

1. A steam water-lifter, comprising a working chamber, a spraying device therein and an injector adjustable with relation to the spraying device. 80

2. In a steam water-lifter, a pressure-chamber, a working chamber, an injector-pipe extended into the working chamber, a spraying-cone above the pipe, and means for adjusting the pipe toward and from the cone. 85

3. In a steam water-lifter, two pressure-chambers, two working chambers, injector-pipes leading into the working chambers, spraying-cones supported rigidly at the inner ends of the pipes and outside thereof, means for adjusting the pipes with relation to the cones, and flexible tubes for connecting the injectors with chambers. 90

In testimony whereof I have hereunto set my hand, in presence of two subscribing witnesses, this 20th day of December, 1901.

PAUL HAUSSMANN.
